GOLF PRACTICE PUTTING CUP

Norman Cohen, 4-19 Banta Place,
Fair Lawn, N.J. 07410

Filed Oct. 6, 1967, Ser. No. 8,890

Term of patent 14 years

(Cl. D34—5)

Fig. 1.

Fig. 2.

FIGURE 1 is a front top perspective view of a golf practice putting cup embodying my new design,

FIG. 2 is a rear top perspective view thereof,

FIG. 3 is a top plan view thereof,

FIG. 4 is a front elevational view thereof taken on line 4—4 of FIG. 3,

FIG. 5 is a longitudinal sectional view taken on line 5—5 of FIG. 4, and

FIG. 6 is a side elevational view taken on line 6—6 of FIG. 3.

I claim:

The ornamental design for a golf practice putting cup, substantially as shown.
